UNITED STATES PATENT OFFICE.

BERNARD BARROW, OF BARROWS STORE, VIRGINIA.

PNEUMATIC TIRE.

1,189,654.

Specification of Letters Patent.

Patented July 4, 1916.

Application filed November 9, 1914. Serial No. 871,151.

To all whom it may concern:

Be it known that I, BERNARD BARROW, a citizen of the United States, residing at Barrows Store, in the county of Brunswick, 5 State of Virginia, have invented certain new and useful Improvements in Pneumatic Tires; and I do hereby declare the following to be a full, clear, and exact description of the invention, such as will enable others 10 skilled in the art to which it appertains to make and use the same.

This invention relates to new and useful improvements in pneumatic tires.

It is within my knowledge that many attempts have been heretofore made to provide inner liners for the shoes of pneumatic tires but these liners, while they have been more or less successful, have not been entirely satisfactory due to certain inherent 15 faults. For instance liners have been provided which are made of rubber, fabric or other suitable material and which in use have been placed between the inner tube and the shoe. These liners of which I speak do 20 not extend completely around the shoe but only for a portion of the distance and are so placed within the shoe that they overlie the inner tube at a point where the shoe is either worn completely through or is weak. While 25 the liners of this type are successful in preventing blow-outs when they are new there is a tendency for the said liners to creep so as to leave the hole in the shoe uncovered. Furthermore the constant pressure caused 30 by the air in the inner tube tends to force the liner out through the hole or weak portion in the shoe and thus increases the size of the hole. This is because of the fact that the liner does not extend completely around the 35 shoe. There has been another type of liner used which consists of a strip of material extending completely around the inner tube and located between the inner tube and the shoe. The edges of this liner are brought 40 together and are located between the edges of the shoe. While this type of liner has been used to a certain extent it, too, has certain disadvantages. For instance after it has 45 been used for a short time it becomes wrinkled and the edges become upset so that when it is desired to replace the liner after it has once been removed it is exceedingly difficult to do so, and especially so that it will lie entirely flat within the casing and so that it 50 will not injure the tube. This upsetting of the edges of the liner is caused, to a great

extent, by the tendency of the liner to creep, which results in the pulling and stretching of the liner at points. Inasmuch as these liners are objectionable for the above noted 50 reasons they must be replaced from time to time and consequently the cost of maintenance will be great, even as is the initial cost.

It is an object of the invention to provide a tire which includes a liner which will 65 neither creep nor permit the inner tube to blow-out through a hole or weak portion in the shoe and in obtaining these results I employ a liner which neither covers only a portion of the tube adjacent a worn out or 70 weak portion of the shoe nor is provided with single thickness edges but I do employ one which covers the entire inner tube and is provided with reinforced edges which act not only to prevent the upsetting of the edges 75 but also to prevent the creeping of the liner.

In constructing a tire in accordance with my invention I employ a shoe which has weak portions or holes therein and a similar liner of substantially the same diameter. 80

In constructing the said tire I first cut notches in the edges of the liner, insert the inner tube therein, and then roll the liner until the edges overlap. I then bind the liner in this rolled condition by means of 85 ligatures and insert the liner into the shoe. The shoe is then placed upon the rim of a wheel in the usual manner and the inner tube inflated. In assembling the liner and shoe I take particular care in arranging them so 90 that the weak portions of one register with relatively stronger portions of the other.

In the drawings: Figure 1 is a sectional perspective view of a tire constructed in accordance with my invention showing the positions of the parts when the inner tube is inflated; Fig. 2 is a fragmental perspective view of the liner showing the notches cut therein, and Fig. 3 is a sectional perspective view of the liner when it is rolled 95 and bound by the ligatures and before the inner tube has been inflated.

Referring to the drawing by reference characters wherein like parts are indicated by like characters throughout the several views: In the embodiment of the invention shown in the drawing, I have illustrated the tire shoe 1 which is provided with beads 2 on its edges so that it may be secured to the rim 3 of the wheel. Located within this shoe 1 is a liner 4 which is of substantially 100 the same normal shape as the shoe 1. An

inner tube 5 is located within the liner 4. When the inner tube is inflated the bead 6 on one edge of the liner 4 is located between the beads 2 on the shoe 1. The bead 6' on the other edge of the liner is passed inwardly and beyond the edge on which the bead 6 is located as clearly illustrated in Fig. 1 of the drawing. Notches 7 are cut in registration and are adapted to permit the valve stem of the inner tube to pass therethrough. It will be noted that the rubber face of the liner contacts with the inner fabric face of the shoe 1 and it has been found by actual experience that this particular arrangement causes the rubber on the liner to gum so that it virtually forms a cement which secures the liner to the shoe. This is particularly advantageous in that it will prevent the entry of dirt and moisture between the liner and the shoe through such an opening as disclosed at 8 in Fig. 1.

It will be noted that the pressure caused by the inner tube will bind the bead 6 between the beads 2 on the shoe and also bind the bead 6' on the opposite edge of the liner against the inner face thereof. This will prevent the creeping of the liner within the shoe. It will be further noted that the liner is so arranged that a continuous smooth surface is provided against which surface the inner tube bears.

It is to be noted that the presence of the beads 6 and 6' on the liner will effectively prevent blow-outs where the shoe becomes weak or worn because of the pressure against the rim 3. It is of course obvious that the shoe will become weak and worn at the point where it contacts with the rim 3 and if it were not for the presence of the beads 6 and 6' the pressure within the tire would cause the edges of the liner to blow out through the weak or worn portions of the shoe. On the other hand the presence of these beads effectively prevents any blow-out of the liner and consequently of the in-

ner tube through any weak or worn portion of the shoe at points adjacent to the rim or even at points remote from the rim.

From the foregoing description it will be seen that I have provided a tire which includes an inner liner which will effectively prevent blow-outs through the weak portions of the shoe and which will not creep within the shoe and which will further maintain its original shape. Furthermore I have provided a tire which will be exceedingly inexpensive to manufacture and of which the cost of maintenance will be small.

While I have illustrated and described a particular embodiment of my invention, it has merely been for the sake of convenience and I do not wish to be limited to that particular embodiment as it is obvious that numerous changes may be made in the details of construction without departing from the spirit of the invention or exceeding the scope of the appended claims.

What I claim is:—

1. In a pneumatic tire, the combination with a shoe adapted to have its edges attached to a rim, of a liner having beads on the edges thereof, one of said beads being disposed between the edges of the shoe and the other of the beads being disposed above the first mentioned bead. 70

2. The combination with a rim, of a tire shoe having its edges held therein and in spaced relation to each other, a liner having beads on the edges thereof, one of which beads is disposed between the edges of the shoe and the other of which beads is disposed above the first mentioned bead and in contact with the inner face of the liner, and an inner tube disposed within the liner. 80

In testimony whereof, I affix my signature, in the presence of two witnesses.

BERNARD BARROW.
